UNITED STATES PATENT OFFICE

169,899

SOCK DISPLAY FORM

Hollis M. Fisk, Oakland, Calif., assignor to
John A. Delamater, San Francisco, Calif.

Application March 15, 1952, Serial No. 18,911

Term of patent 14 years

(Cl. D80—8)

To all whom it may concern:

Be it known that I, Hollis M. Fisk, a citizen of the United States, residing at 240 Grand Avenue, Oakland, State of California, have invented a new, original, and ornamental Design for a Sock Display Form, of which the following is a specification, reference being had to the accompanying drawing, forming a part hereof.

Fig. 1 is a top plan view of a sock display form showing my new design.

Fig. 2 is a front view.

Fig. 3 is a side view.

I claim:

The ornamental design for a sock display form, as shown.

HOLLIS M. FISK.
